US00D835363S

(12) **United States Design Patent** (10) **Patent No.:** **US D835,363 S**
Hebert (45) **Date of Patent:** **** Dec. 4, 2018**

(54) **CAT SCRATCHER**

(71) Applicant: **Eric Michael Hebert**, Harrisburg, NC (US)

(72) Inventor: **Eric Michael Hebert**, Harrisburg, NC (US)

(73) Assignee: **fairly Odd Treasures, LLC.**, Harrisburg, NC (US)

(**) Term: **15 Years**

(21) Appl. No.: **29/587,281**

(22) Filed: **Dec. 12, 2016**

(51) **LOC (11) Cl.** **30-99**

(52) **U.S. Cl.**

USPC **D30/160; D30/158**

(58) **Field of Classification Search**

USPC ..... CLAIM

The ornamental design for a cat scratcher, as shown and described.

DESCRIPTION

FIG. 1 is a perspective view of a cat scratcher showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

1 Claim, 5 Drawing Sheets
